UNITED STATES PATENT OFFICE.

RICHARD BECKMANN, OF CHARLOTTENBURG, GERMANY.

RECEPTABLE FOR TOOTHPICKS.

No. 863,896.

Specification of Letters Patent.

Patented Aug. 20, 1907.

Application filed July 3, 1906. Serial No. 324,573.

To all whom it may concern:

Be it known that I, RICHARD BECKMANN, residing at Charlottenburg, Germany, have invented certain new and useful Improvements in Receptacles for Toothpicks; and I do hereby declare the following to be a full, clear, and exact description of the invention, such as will enable others skilled in the art to which it appertains to make and use the same.

My invention relates to a preferably dust-tight receptacle for toothpicks, having a device for delivering the contents singly. In this apparatus the front toothpick of an assemblage, acted upon by spring or other pressure, is delivered from the receptacle by a sliding or rotary member, which bears against the face of the tooth-pick and feeds it forward by friction.

The advantage of the new receptacle over prior like apparatus is that the tooth-picks are infallibly engaged and delivered by the feed-member, no matter what their shape and thickness. It is thus impossible for the delivery-mechanism to get out of order through jamming of the tooth-picks or through two picks being fed forward simultaneously.

My invention is illustrated in the accompanying drawing, in which Figure 1 is a front elevation and part section of a form of the new apparatus in which a sliding feed is employed. Fig. 2 is a cross section through Fig. 1. Fig. 3 is a fragmentary horizontal section on the line A--B of Fig. 1. Fig. 4 is a front elevation and part section of a modified construction of the apparatus, in which a rotary feed is used. Fig. 5 is a cross section through Fig. 4.

Referring more particularly to Fig. 1--3, the holder consists of a box-shaped receptacle *a*, surrounded by a casing *a'* (indicated in the figures by dotted lines), and of suitable dimensions to receive the toothpicks *b*, preferably loosely assembled together one behind the other. To enable the receptacle *a* to be filled, one of its walls is arranged to flap back or slide. Against the backmost of the assembled toothpicks, which are arranged to slide in the receptacle *a*, there presses a plate *c*, loosely guided in the receptacle. This plate *c* has a lateral stud *d*, which engages in a guide-slot *e* in the one side of the receptacle. The pin receives the lower end of a guide-arm *f*, the upper end of which is bifurcated at *g* and embraces a pin *h* projecting from the wall of the receptacle *a*, the head *i* of the pin retaining the arm *f* in place. Against the stud *d* there presses the free end of a spiral spring *k*, secured at the bottom of the receptacle *a*, which spring tends to advance the plate *c* and the assemblage of toothpicks *b* in direction of the arrow (Fig. 1).

The guide arm *g* prevents the plate *c* from tilting axially upon the pin *d* which is arranged at its middle part, when the plate is being pushed backward in the empty receptacle.

At the front end of the case *a* is a slide *m*, which is provided with a roughened or toothed part *n*, against which the front toothpick of the assemblage is pressed owing to the action of the spring *k*. The slide *m* is provided at the bottom with a stud *o*, which is embraced by the slotted end *p* of a double-armed lever *r*, which is fulcrumed so as to turn on the axis *s*, mounted in the receptacle walls and is acted upon by a spring *t*. The rear end of the lever *r* is furnished with a knob *u*.

When the knob *u* is depressed, the slide *m* is lifted by the lower end of the lever *r* and the front toothpick *b* is fed through the slot *v* in the top of the receptacle *a* to such an extent that it can be conveniently grasped and withdrawn from the apparatus, as indicated by the dotted lines in Fig. 1. On release of the knob *u* the lever *r* is returned to its initial position by the action of the spring *t*, the slide *m* being retracted simultaneously. The teeth of the part *n* of the slide *m* may be of any suitable description, but are preferably upwardly directed, as shown in Fig. 1, so as to admit of the readiest possible return of the slide to its lowermost position.

The apparatus illustrated in Fig. 4 and 5 differs from that just described inasmuch as the reciprocating slide *m* is replaced by toothed wheel *w* mounted on an axis *z* in the upper part of the receptacle *a*, against which wheel the here horizontally disposed tooth-picks *b* are pressed by spiral springs *x* arranged at each side of the receptacle. The exit *y* for the toothpicks is located in the end wall of the receptacle *a*, as Fig. 4 shows. The end of the axis *z* is provided with a knob *j* to enable the wheel *w* to be readily rotated for the purpose of feeding forward the toothpicks *b* in succession.

Having thus described my invention, what I claim as new and desire to secure by Letters Patent is:

1. The combination, with a receptacle for the articles having a guide slot and an outlet opening, of a toothed feeding device provided with an operating handle for moving it to protrude the articles through the said opening, a feed-plate slidable in the said receptacle and operating to press the articles into contact with the teeth of the said feeding device, a pin secured to the said feed-plate and projecting through the said slot, and a feed spring arranged outside the said receptacle and connected to the projecting end portion of the said pin.

2. The combination, with a receptacle for the articles provided with a single guide slot at its middle part and having also an outlet opening for the articles, of a feeding device for protruding the articles through the said opening, a feed-plate slidable in the said receptacle and provided with a pin which projects through the said guide slot, a guide connected to the said pin and preventing the said feed-plate from tilting, and a feed spring for the said feed-plate.

3. A toothpick receptacle, comprising, in combination, a box, having an exit, to receive the picks; a spring-actuated plate behind the picks and forcing them toward the exit; means for guiding the plate; a roughened feed-plate located in front of the picks, at the exit; and a spring-actuated double armed lever fulcrumed on the box and having

its lower end jointed to the feed-plate, whereby on depression of the other lever-arm the feed-plate rises and advances the foremost pick by friction through the exit; substantially as described.

- 5 4. A toothpick receptacle, comprising, in combination, a box, having an exit and a slotted wall, to receive the picks; a spring-actuated plate located behind the picks and having a lateral stud projecting through the box-slot; a pin on the box-wall; a lever having a forked upper end 10 embracing the pin and a lower end receiving the stud; a roughened feed-plate located in front of the picks, at the

exit, and having a stud at its lower end; and a spring-controlled double-armed lever fulcrumed on the box and having a slotted lower end which embraces the feed-plate stud; all operating substantially as described.

15

In testimony whereof I affix my signature, in presence of two witnesses.

RICHARD BECKMANN.
